UNITED STATES PATENT OFFICE.

DANIEL A. ROBERTS, OF ELMIRA, NEW YORK.

MANIFOLDING COPY BOOK OR PAD.

No. 874,439.

Specification of Letters Patent.

Patented Dec. 24, 1907.

Application filed August 18, 1906. Serial No. 331,206.

To all whom it may concern:

Be it known that I, DANIEL A. ROBERTS, a citizen of the United States, residing at Elmira, in the county of Chemung and State of New York, have invented certain new and useful Improvements in Manifolding Copy Books or Pads, of which the following is a specification.

This invention relates to improvements in the books or pads used by merchants and others in taking manifold copies of orders, etc.; and the object of my invention is to provide means for manipulating the leaves of the book or pad without touching the carbon, or transfer, sheet with the fingers.

I attain my object by constructing the leaves of the book or pad in the manner illustrated in the accompanying drawings, in which—

Figure 1 represents a perspective view of a manifolding sales book embodying my improvements with the carbon sheet stapled in with the leaves of the pad and overlying the uppermost of said leaves; Fig. 2, a similar view of the book, with the uppermost original leaf drawn out from under the carbon sheet and laid down upon said sheet in position for writing an order thereon and transferring said order, through the medium of the carbon sheet, to the underlying copy leaf.

Like letters of reference designate like parts in the two views.

The sales book illustrated in the drawings comprises a pad of leaves made up of pairs of leaves constituting original and duplicate leaves, the duplicate leaves being provided with projecting stubs at one end which are stapled together at B, and the original leaves being attached to the opposite end of the duplicate leaves and interfolded between said leaves, said original leaves being shorter than the duplicate leaves by the width of the stub. The duplicate leaves are rendered detachable from the stub by a perforated line (not shown) and the original leaf is rendered detachable from the duplicate by a perforated line (not shown). This constitutes what is known to the trade as the paragon or interfolded pad, a common and well known form of pad for sales book purposes.

Stapled in with the leaves of the pad is a carbon, or transfer, sheet C designed to completely overlie the surface of the leaves of the pad; and the pad is usually supplied with a cover, as indicated at D, to which the pad is attached in any desirable manner.

In the two views, E indicates the original leaf of the uppermost pair of leaves, and F the duplicate leaf, said leaves being joined together at the crease G, the line of jointure being perforated to render the leaves easily detachable one from the other.

In manipulating a book of this character, it is required to draw out the uppermost original leaf from under the carbon sheet and lay it down upon the carbon sheet, in order that the matter written upon the original may be transferred to the underlying duplicate. Unless some means be provided to avoid it, the carbon sheet must be taken hold of and lifted away from the underlying original leaf in order to get hold of said leaf to draw it out from under the carbon sheet. This rubs the carbon and smuts the fingers. To avoid this handling of the carbon sheet, I provide the original leaves at one side, and preferably near the free ends of the leaves, with a projecting ear H. This ear enables the user to take hold of the leaf with his thumb and fingers and to draw the leaf out from under the carbon sheet without touching said sheet. This is done by placing the thumb on the ear and pressing the leaf downwardly away from the stub, or to one side, until the ear can be grasped between thumb and finger, after which it is a simple matter to draw out the leaf and place it above the carbon sheet without touching said sheet with the hands.

In Fig. 2 I have shown the original leaf E as having been drawn out from under the carbon sheet and laid down in position thereover for writing, one of the intermediate positions of said original leaf being indicated in broken lines. When the original leaf is drawn back, as in the position shown by the broken lines, it will be evident that the carbon sheet will drop down into place upon the underlying duplicate leaf and that no handling of the carbon sheet will be required. After the writing is done the original and duplicate leaves are detached from the stub at one and the same time, permitting the carbon sheet to fall upon the next original leaf.

In order that the ears H on the original leaves may be properly supported and maintained in place, I preferably provide corresponding ears on the duplicate leaves. These ears on the duplicate leaves, in some forms of pads, may also be used in withdrawing them from under the carbon sheet

when detaching them from the pad. It will, of course, be understood that the size, shape and location of these ears may be changed without departing from the spirit of my invention; also that said ears may be arranged on one side or the other of the pad, and that I may provide them on both sides, if that be desirable. By providing these projecting ears where it is required to take hold of the leaves to withdraw them from under the carbon sheet, I am enabled to make the carbon sheet of the full width of the leaves of the pad from top to bottom of the writing surface, thereby insuring that any matter written upon the original leaf, no matter where it may be upon said leaf, will be transferred in full upon the underlying duplicate leaf. In sales books it is especially essential that there shall be no projection of the original leaf beyond the sides of the carbon sheet where the entries of charge and credit are made. I, therefore, locate the ears H at a point somewhere above the space ruled for these entries, as shown in Fig. 2 of the drawings.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having thus described my improvement, what I claim as my invention and desire to secure by Letters-Patent is:

1. In a device of the class described, a pad comprising a plurality of leaves each of which is provided with a portion which projects beyond the body of the pad, said projecting portions lying one above the other and in register with one another.

50 2. In a device of the class described, a pad comprising a plurality of leaves connected together at the stub end of the pad, and an overlying carbon sheet, each of said leaves being provided with a portion which projects outwardly beyond the body of the pad.

3. In a device of the class described, a pad comprising a plurality of leaves connected together at the stub end of the pad, an overlying transfer sheet, and an ear upon each of said leaves which extends outwardly therefrom beyond the body of the pad and said transfer sheet, whereby said leaves may be grasped and manipulated without touching said transfer sheet.

65 4. In a device of the class described, a pad

comprising a plurality of sheets each of which is folded into a plurality of leaf portions, said sheets being secured together at the stub end of the pad, a transferring medium attached to said sheets and adapted to be inserted between the leaf portions thereof, and an ear provided upon one of the leaf portions of each sheet by means of which the sheet may be grasped and manipulated with relation to the transferring medium without touching the latter.

5. In a device of the class described, a pad comprising a plurality of leaves connected together at the stub end of the pad, an overlying transfer sheet attached thereto, each of said sheets being folded at a point remote from the stub end of the pad into a plurality of leaf portions between which the transfer sheet may be inserted, and an ear upon one of the leaf portions of each sheet whereby said sheet may be grasped and drawn from beneath the transfer sheet without touching the latter.

6. In a device of the class described, a pad comprising a plurality of sheets each of which is folded upon itself at the lower end of the pad to form original and duplicate leaf portions, a transferring sheet secured to the stub end of the pad and adapted to be inserted between said leaf portions, and an ear provided upon the leaf portion of each of said sheets.

7. In a device of the class described, a pad comprising a plurality of sheets each of which is folded upon itself to form original and duplicate leaf portions, corresponding leaf portions of said sheets being secured together at the stub end of the pad, a transferring sheet secured to the stub end of the pad and adapted to be inserted between the leaf portions of each of said sheets, and an ear upon the corresponding leaf portion of each of said sheets which projects outwardly beyond the body of the pad by means of which said leaf portion may be grasped and drawn from beneath the transferring sheet.

8. In a device of the class described, a pad comprising a plurality of sheets each of which is folded upon itself to form a duplicate leaf portion and an original leaf portion, corresponding leaf portions being fastened together at the stub end of the pad, an overlying transfer sheet secured to the stub end of the pad and adapted to be inserted between the leaf portions of each of said sheets, and an ear provided near the top of the lateral edge of corresponding leaf portions of each sheet, said ears projecting laterally beyond the body of the pad.

9. In a device of the class described, a pad comprising a plurality of sheets each of which is folded upon itself to form an original leaf portion and a duplicate leaf portion, corresponding leaf portions being fastened together at the stub end of the pad, a trans-

- ferring sheet secured to said pad at the stub end thereof and adapted to be inserted between the leaf portions of each of said sheets, and an ear provided upon the original and 5 duplicate leaf portions of each of said sheets by means of which the former leaf portion may be drawn from beneath the transferring sheet or the latter may be detached from the pad.
- 10 10. A manifolding book or pad comprising a plurality of leaves and an overlying carbon or transfer sheet, said leaves being provided with projecting ears exposed at one side of the carbon sheet beyond the body of the pad, 15 whereby the leaves may be grasped in manipulating them with relation to the carbon sheet without handling said sheet.
11. The combination, in a manifolding book or pad, of a carbon or transfer sheet 20 normally resting upon the top of the pad and overlying the leaves thereof, the leaves at their free ends being concealed by the carbon sheet, and being provided at one side with ears which are exposed beyond the body of the pad. 25
12. In a device of the class described, a pad comprising a plurality of connected leaves, and an overlying carbon sheet, certain of said leaves being provided with a portion which projects outwardly beyond the 30 body of the pad.
13. In a device of the class described, a pad comprising a plurality of leaves connected together at the stub end of the pad, an overlying carbon sheet, and an ear upon 35 certain of said leaves which extends outwardly therefrom beyond the body of the pad and said carbon sheet whereby said leaves may be grasped and manipulated without touching said carbon sheet. 40

In testimony whereof I have affixed my signature, in presence of two witnesses.
